ULTRA HIGH FREQUENCY ANTENNA

Lester G. Zukerman, Hollywood, Calif., assignor
to Lockheed Aircraft Corporation, Burbank,
Calif.

Application February 25, 1941, Serial No. 380,516

5 Claims. (Cl. 250—33)

This invention relates to an ultra high frequency antenna, and/or antenna mast, especially adapted for aircraft use; and is intended to provide an improved means of mounting and insulating such a mast or antenna from the metal skin of an airplane fuselage.

An external radio antenna, whether of the vertical radiator, or horizontal wire type, requires an electrical lead-in passage which insulates the antenna and its associated transmission line from the hull or fuselage. The present invention relates to such a dual purpose insulating passage, and provides an improved insulating structural mounting for the antenna that is readily removable and to which various types of antenna can be applied which may be of such lengths as to tune to the desired ultra high frequencies. The mounting of this invention provides smoothly faired contours from the streamlined mast to the skin of the fuselage, thus making for low turbulence and low aerodynamic drag, as well as absence of external crevices and the like that would facilitate the collection of dirt which would tend to bridge the dielectric and thereby reduce the resistance of the leakage path.

It is accordingly an object of this invention to provide an improved and simplified means of mounting an end-fed ultra high frequency antenna on an all metal aircraft. The antenna is formed as a streamlined shell of sheet metal, and may be fed by the inner conductor of a coaxial feeder cable connected thereto through the hollow center of an insulating mounting block. The outer conductor of the coaxial feeder cable connected thereto through the hollow center of an insulated mounting block. The outer conductor of the coaxial cable terminates at the mounting block, which insulates it from the antenna, so that it can be at ground potential, or above, as desired. The use of a coaxial cable so connected to the insulated mast renders the connection impervious to dirt or foreign matter which might otherwise affect the electrical characteristics of the coupling.

It is a further object of this invention to provide an improved and simplified dielectric mounting block and/or mast for a fixed antenna, which block is readily applied to and removed from the shell or skin of an airplane and which is adapted to receive interchangeable streamlined antenna shells tuned to different frequencies, which shells are also adapted to support conventional wire antennae if so desired.

Other and further objects of this invention

will become apparent as the description of the invention proceeds.

This invention, in a preferred form is shown in the accompanying drawing, wherein:

Figure I is a fragmentary side view of the nose of an airplane fuselage in which an antenna embodying the features of this invention has been installed.

Figure II is an enlarged inside view of the base 10 of the mast, as mounted in the fuselage, the view being indicated by the section line II—II in Figure I.

Figure III is a longitudinal section of the antenna, on the line III—III of Figure II.

Figure IV is a fragmentary section through the supporting block, on the line IV—IV of Figure III.

As shown on the drawing:

It will be appreciated that while the antenna 20 of this invention is shown as depending from the lower surface of an airplane fuselage or cabin 10, it is equally adaptable for top or other mountings.

The usual structure of an all metal fuselage 25 comprises a skin 11 supported by transverse bulkhead rings 12, and longitudinals 13, one panel thereof being shown in Figure II, wherein an inner skin panel 14 is arranged to bridge the panel space between adjacent bulkhead rings to provide for clamping the base 15 of an antenna block 16 against the outer skin 11.

The antenna block 16 is preferably formed by a compression molding process from a plastic having good dielectric, and the necessary physical and chemical properties. Polymerized styrene is 35 an example of a suitable material having extremely low loss electrical characteristics. While the block, as disclosed herein, can be conveniently molded as a single piece, it is possible to make it as two or more pieces subsequently joined by cementing together. The mast 16 is formed as a streamlined cylinder having a central cored hole 17, the cylinder conforming to the inside dimensions of an antenna shell 18 of 40 streamlined form, the open end of which slips over the mast and is retained in place by a series of countersunk screws 19 engaging a gang of elastic stop nuts 20 in the central hole 17. The antenna shell 18 is preferably dimpled for the heads of the screws 19, and grooves 21 are formed in the sides of the mast 16 to permit assembly 45 and removal of the dimpled shell 18.

It will be noted that the dielectric mast 16 and the corresponding part of the antenna shell 18 are of substantially parallel streamlined cylinder

construction, while the balance of the shell 18 tapers to a narrow end while maintaining its streamline form. If the mast and shell are to be used to support a wire type of antenna 22, a plate 23 is welded into the shell near its outer end, and a connecting link 24 is bolted thereto to support suitable antenna wires 25. The wire antenna may use the shell 18 as a lead in, or a separate lead-in wire 26 may be used as shown if the antenna shell 18 is to be used in a separate circuit.

The shell 18 is electrically connected to a central pin 27 in a detachable plug receptacle 28 by means of an extension piece 29 carrying a nut engaged by the innermost screw 30 shown in Figure IV. The receptacle 28 is mounted in an enlargement of the central hole in the mast 16, being exposed on the inner surface of the base 15. With this arrangement the electrical connection can be broken at the receptacle 28 and the various screws 19 and 30 removed to remove the antenna shell 18, which shell can be replaced with another, tuned to a different wave length. The base and mast can also be removed from the skin of the fuselage and replaced by a closure using the same screw holes that mounted the base 15.

Inasmuch as the cylindrical portion of the mast 16 acts as a cantilever beam, material may conveniently be removed from the trailing edge as at 31, without affecting the strength, as a full bearing surface would still remain ahead of the major diameter normal to the streamline axis.

It will be noted that the assembly, installation, and servicing of this unit and its electrical connections is especially convenient. It is desirable, but not necessary to add reinforcement 32 to the inside of the skin 11, about the aperture therein through which the mast projects, and to provide a rubber-like gasket 33 between the skin and the base 15 of the dielectric. The completely assembled mast may be inserted into position from the inside of the fuselage and bolted in place by screws and nuts 34 extending through the skin, gasket, base 15, and inner skin 14, to clamp the assembly together; the inner skin being additionally secured to the bulkhead rings 12.

It will thus be seen that I have invented an improved and simplified ultra high frequency antenna, which can also be used as a mast supporting wire antennae for other frequencies.

Having thus described my invention and the present preferred embodiment thereof, I desire to emphasize the fact that many modifications may be resorted to in a manner limited only by a just interpretation of the following claims.

I claim:

1. An antenna mast construction, comprising a streamlined radiator shell of the desired ultra high frequency characteristics, and supporting

5 and insulating means therefor, comprising a dielectric member having an outstanding projection adapted to telescope into said radiator shell and a base adapted to be secured to a supporting surface in faired relationship to the radiator supporting projection, and means providing a detachable electrical connection from said radiator shell to the interior surface of said dielectric base.

2. An antenna mast construction comprising a base member of dielectric material adapted to be flush mounted relative to its vehicle, a streamlined cylinder of said material projecting outwardly from the base member and having a passage therethrough, gang nuts arranged in said passage, an ultra high frequency antenna comprising a shell adapted to be engaged over said streamlined cylinder and removably secured to said gang nuts through the material of said member, and a lead-in connection extending through the dielectric material to a connection with said shell.

3. An ultra high frequency radio radiator comprising a streamlined shell, and mounting means for supporting said shell in insulated relationship to the skin of an all metal airplane, comprising a passaged base of dielectric material secured to said skin and having an outwardly projecting mast engaging said radiator shell whereby to support the same in insulated relationship to said skin, side channels formed in said mast to receive dimples formed in the shell, countersunk fastening means extending from said dimples to the passage in said base and mast, and a lead-in connection extending through said passaged base into electrical connection with one of said fastening means.

4. An ultra high frequency radio radiator comprising a streamlined shell, and mounting means for removably supporting said shell in insulated relationship to the skin of an all metal airplane, comprising a passaged base of dielectric material removably secured to said skin and having an outwardly projecting mast removably enveloped by said radiator shell whereby to support the same in insulated relationship to said skin, fastening means extending from the shell to the passage in said mast, and a lead-in connection extending through said passaged base into detachable electrical connection with said fastening means.

5. An airplane radio antenna radiator comprising a streamlined shell, and supporting means therefor comprising a dielectric having a base secured to the skin of said airplane and a streamlined projection fitting into the base of said shell, said dielectric being apertured for removable fastening means extending transversely from said shell, and a lead-in wire connection insulated from the skin of the airplane.

LESTER G. ZUKERMAN.
